UNITED STATES PATENT OFFICE.

FRANK A. HOWARD, OF ELIZABETH, NEW JERSEY, ASSIGNOR TO STANDARD DEVELOPMENT COMPANY, A CORPORATION OF DELAWARE.

ART OF CONVERTING HYDROCARBON OILS INTO LOWER BOILING PRODUCTS.

Application filed August 16, 1922. Serial No. 582,113.

My invention relates to the art of cracking or obtaining lighter products from hydrocarbons by aid of heat, and will be fully understood from the following description taken in connection with the accompanying drawing which represents semi-diagrammatically one form of embodiment of the invention.

In subjecting hydrocarbons to heat in the present types of apparatus a general difficulty encountered is the occurrence of localized overheating. Where working at the relatively high temperatures of pressure distillation or cracking, coke patches and hot spots develop on the still or tube walls, occasioning not only a rapid deterioration of the apparatus, but necessitating not infrequently a premature discontinuance of the run.

By the present invention I avoid such undue and irregular concentration of heat upon areas of the still, or tubes, or other heating surface, as would be primarily favorable to the starting of spot coking, and I am moreover enabled to transmit heat into the oil in the still by a much lower temperature gradient from the heating side.

Referring more particularly to the drawing, reference character 1 designates a suitable means for holding oil while being heated, and which may be, for example, a shell still or a cracking drum or tube or assembly of tubes. Leading from the oil heater is an outlet pipe. In the case of a still this will more particularly be a vapor pipe 3 connecting with a reflux condenser 4, and proceeding therefrom is a pipe 5 leading to a suitable water-cooled condenser 6 and receiving tank 7. A run-back pipe 16 is provided for returning reflux from condenser 4 to the still, and a pipe 17 may be used to by-pass the reflux condenser when desired, the valves 18 and 19 being closed on such occasions and valve 20 being opened. Spaced about the wall of the oil heater is a casing 8 which forms a jacket for a heating fluid delivered at an advantageous distributing point by a pipe 11 from a suitable boiler 12 mounted in a furnace chamber 10. The detailed construction of the boiler may advantageously be, for instance, that set forth in the application of F. A. Howard, W. K. Lewis and H. M. Noel, Serial No. 551,300, filed April 10, 1922; and I employ as heating medium mercury or a suitable vaporizable non-

corrosive inorganic salt or organic compound. Mercury is advantageous in that its vapors are available at a range of temperatures suitable and the pressures remain within very moderate limits, for instance at a gauge pressure of 40 pounds the saturated mercury vapors have a temperature of about 833° F. The vapors may also be superheated if desired.

And with any of the materials contemplated, temperatures up to 1000° F. may be attained without the pressure of the medium exceeding 200 pounds.

A return pipe 14 completes the circuit for the used heating medium back to the boiler, and it will be understood that the jacket and boiler circuit is a closed system which is exhausted of air and sealed after the charge of heat-transmitting medium has been originally placed in the boiler.

Suitable thermometers and pressure gauges (not shown) are provided on the boiler and still, also control valves on the lines 11 and 14.

A covering of insulation 9 is provided about the oil heater to cut down unnecessary heat losses.

In operation, hydrocarbon oil of desired character is charged into the oil heater 1 or is fed continuously therethrough and the heating fluid is supplied from the boiler at the desired temperature, for instance between 700° and 1000° F., depending somewhat upon the particular oil employed, precise regulation being secured by controlling the pressure in the heating jacket. The distillation vapor passes over through the vapor line 3, is freed of undesirable heavy constituents by the reflux condenser 4 and is finally condensed in the water-cooled condenser 6. The reflux condenser, however, may be bypassed, if desired, by opening valve 20 and closing the valves 18 and 19. Whatever pressure is desired in the oil heater 1 is maintained by adequate closure or regulation of the valve 15 on the gas-line from the receiving tank or by a valve 21 in front of the condenser 6 if it is preferred not to hold the condenser under the same pressure as the still. In some cases temperature regulation may be secured by controlling the pressure. By leaving all valves open, the pressure can be maintained substantially atmospheric, but generally I prefer higher pressures, for instance 100 lbs., 350 lbs., etc. While, as cus-

tomary, the run may continue down to tar bottoms, I also contemplate, where using a shell still, running the oil down to complete dryness, obtaining in this manner a materially increased yield. Where applying my invention to tube stills or cracking coils in which a gang of tubes is employed, the entire gang may be enveloped in the heating jacket or the tubes may be individually jacketed as may be preferred.

10 The advantages of my invention while in practice mostly desired with liquid oils, extend also to solid materials from which light hydrocarbons may be distilled off.

15 While in describing my invention I have referred to certain specific details, it will be understood that this is with the intent of explanatory illustration rather than limitation. Nor is the invention to be considered 20 as in any way dependent upon the accuracy of any theories or reasons advanced to explain the advantageous results attained. On the contrary, it is limited only as defined in the following claims, in which it is my intention to claim all inherent novelty as 25 broadly as the prior art permits.

What I claim is:—

1. Process of cracking hydrocarbons, comprising heating in a closed system a substance which at a temperature of 700° to 30 1000° F. exerts a pressure of less than 200 lbs. per sq. in. and is stable against decom-

position at such temperatures, subjecting the hydrocarbon to indirect heat of the vapors of such substance within the temperature range specified, whereby the hydrocarbons are cracked by uniformly applied heat, taking off vaporous cracked products, and condensing the same.

2. Process according to claim 1, in which the hydrocarbons are distilled substantially to dryness.

3. Process of cracking hydrocarbons, comprising heating mercury in a closed system to a temperature above 700° F., subjecting the hydrocarbons to indirect heat of the mercury vapor at such temperature, whereby the hydrocarbons are cracked by uniformly applied heat, taking off vaporous cracked products, and condensing the same.

4. Apparatus for cracking hydrocarbons, comprising a still, a vapor pipe leading from said still, a condenser for vapors from the still, a casing about the still, and a heating system for the still and including means for supplying to the casing at a temperature above 700° F., a vaporized material which at temperatures of 700° to 1000° F. exerts a pressure less than 200 lbs. per sq. in. and is stable against decomposition at such temperatures, said heating system being normally closed against escape of vapors.

FRANK A. HOWARD.
